(57) **CLAIM**

The ornamental design for a packaging device, as shown and described.

DESCRIPTION

FIG. 1 is a top perspective view of a packaging device.
FIG. 2 is a top view of a packaging device.
FIG. 3 is a bottom view of a packaging device.
FIG. 4 is a front view of a packaging device.
FIG. 5 is a rear view of a packaging device.
FIG. 6 is a right side view of a packaging device.
FIG. 7 is a left side view of a packaging device.
FIG. 8 is a top perspective view of a packaging device having a transparent top and bottom in an open position.
FIG. 9 is a top perspective view of a packaging device.
FIG. 10 is a top view of a packaging device.
FIG. 11 is a bottom view of a packaging device.
FIG. 12 is a front view of a packaging device.
FIG. 13 is a rear view of a packaging device.
FIG. 14 is a right side view of a packaging device.
FIG. 15 is a left side view of a packaging device.
FIG. 16 is a top perspective view of a packaging device having a transparent top and bottom in an open position.
FIG. 17 is a top perspective view of a packaging device.
FIG. 18 is a top view of a packaging device.
FIG. 19 is a bottom view of a packaging device.
FIG. 20 is a front view of a packaging device.
FIG. 21 is a rear view of a packaging device.
FIG. 22 is a right side view of a packaging device.
FIG. 23 is a left side view of a packaging device.
FIG. 24 is a top perspective view of a packaging device having a transparent top and bottom in an open position.
FIG. 25 is a top perspective view of a packaging device.
FIG. 26 is a top view of a packaging device.
FIG. 27 is a bottom view of a packaging device.
FIG. 28 is a front view of a packaging device.
FIG. 29 is a rear view of a packaging device.
FIG. 30 is a right side view of a packaging device.
FIG. 31 is a left side view of a packaging device.
FIG. 32 is a top perspective view of a packaging device having a transparent top and bottom in an open position.
FIG. 33 is a top perspective view of a packaging device.
FIG. 34 is a top view of a packaging device.
FIG. 35 is a bottom view of a packaging device.
FIG. 36 is a front view of a packaging device.
FIG. 37 is a rear view of a packaging device.
FIG. 38 is a right side view of a packaging device.
FIG. 39 is a left side view of a packaging device; and,
